BUCKET HOOK

Ernest Roy Blood, Washington, Robert William Lichti,
Oswego, and James Albert Pierson, Aurora, Ill., as
signors to Caterpillar Tractor Co., Peoria, Ill.

Filed May 10, 1972, Ser. No. 252,160

Term of patent 14 years

Int. Cl. D8—08; D12—16

U.S. Cl. D8—232

FIG. 1 is a side elevation of a bucket hook incorporating our new design which is shown in an operational environment on the dashed line representation of an excavator bucket said dashed representation forming no part of the claimed design.

FIG. 2 is a somewhat enlarged side elevation of the design of FIG. 1 with the opposite side thereof being identical to the side shown.

FIG. 3 is a front elevation thereof.

FIG. 4 is a rear elevation thereof.

FIG. 5 is a top plan view thereof.

FIG. 6 is a bottom plan view thereof.

We claim:

The ornamental design for a bucket hook, substantially as shown and described.
